DECORTICATING DEVICE FOR TIMBER

Albert Bezner, Ravensburg, Germany

Application November 26, 1932, Serial No. 644,535
In Germany November 23, 1929

5 Claims. (CL 144—208)

This invention relates to a device for shaving and trimming logs, timber, tree trunks, masts, and the like, and particularly to decorticating or rossing machines of the type described in my co-pending application Ser. No. 497,549, filed November 22, 1930, now Patent #1,921,904 issued August 8, 1933, and of which this application is in part a continuation and in which the timber to be decorticated is turned during the barking process by means of rotatable tappet wheels and, by placing the tappet wheels in an angular position, simultaneously moved forward relative to the barking tool, so that the timber can be shaved by being turned only once.

According to the invention, the tappet wheels on which the timber to be shaved is positioned are disposed on their shafts so that they may be swung about their axes and thus adjusted to the varying diameters of the timber to be treated. For this purpose, the tappet wheel axles are provided with spherical bearing units on which the tappet wheels consisting of one or several parts and being hollow and spherical inside are guided oscillatorily and controlled by an adjusting member. Therefore, the tappet wheels can carry out any swinging motion relative to the shaft while the position of the latter remains unaltered.

By way of example, one embodiment of the invention is illustrated in the accompanying drawings, in which Figure 1 is a side view of a decorticating machine according to the invention; Fig. 2, a top view thereof; Fig. 3, a front view of the tappet wheel frame, partly broken away; Figs. 4 and 5 are, respectively, a cross and longitudinal section of one of the tappet wheels; and Fig. 6 is a longitudinal section of the decorticating tool having the form of a helical cutter.

Referring to the drawings, the mast, log, or timber 1 to be shaved rests on the two driven tappet wheels 2 which are mounted swivelably and turn the log or mast 1 during the barking process and move it forward in axial direction when turned around their axes in the same way out of a vertical plane. The mast or log 1 is worked by the helical cutter 4 rotatably disposed on the free end of the tubular swingable arms 22, 23 and driven, for instance, by the belt 3. In Fig. 2, two tubular arms 22, 23 are shown which are pivotally suspended from the frame 33 so as to swing about the shaft 5 which extends parallel to the longitudinal axis of the mast 1; each of the two arms carrying at its free end a helical cutter 4. Swinging supporting structures having one arm or more than two may be employed also.

As Fig. 6 shows, the helical cutter 4 consists of

the body member 17 firmly positioned on the shaft 20 guided in the two bearings 19 and driven, for example, by the pulley 21, and of the sheet metal band 18 helically attached to the member 17. In Fig. 6, two steel bands 18 are wound in double thread on the body 17, but it is also possible to provide one or several steel bands in one or multiple threads. The circumference of the body member 17 is correspondingly shaped to receive and secure the helical steel bands 18 and provided with fastening surfaces therefor, the bands 18 being preferably exchangeably secured to the body by means of screws. At its outer border the steel band 18 is made into a cutting edge. The band 18 helically wound around the body member 17 may be made also from sheet iron having a cutting edge of high-grade steel welded to it. As shown particularly in Fig. 6, the helical cutter is disposed at an angle of less than 90° relative to the longitudinal axis of the body member.

The cutter shaft 20 is carried by the light metal casing 22 which can be rotated, but not longitudinally displaced, on the swingable arm steel tube 23. To the casing 22 or the tube 23, on either side of the cutting roll, individually adjustable and exchangeable feelers or guards 24 are attached, as shown in Fig. 6, which extend under the casing 22 and engage the surface of the mast or log to regulate the cutting action of the cutter roll and its penetration into the log or timber 1.

Shavings are conveniently drawn off through the casing 22 and the swingable arm steel tube 23. In the double swingable arm arrangement 35 shown, the two swingable arm tubes 23 are connected by a curved or U-shaped terminal member 27 (Figs. 1 and 2) with a joint suction discharge 28.

The tappet wheel frame or bracket 31 is also 40 provided with a suction discharging device 30 for shavings and the like, the bracket 31 having for this purpose below the wheels 2 a hollow space 29, as shown in Figs. 1 and 3, of a form causing the dropping shavings or the like to 45 accumulate at one point whence they can be drawn off by the pipe or tube 30.

The tappet wheels 2 are oscillatorily or swivelably disposed on their shafts of rotation 6 to impart to the timber to be treated forward motion in longitudinal direction in addition to rotary motion. For this purpose there are, for example, spherical units 7 keyed on to the shafts 6 which may be driven by a sprocket 32 or in any other suitable manner, as indicated in Figs. 3 55

- to 5, and these units carry the tappet wheels 2 consisting of two parts 8 connected by screws or other suitable means, said portions being hollow and spherical inside and adapted to receive on 5 their outside the rim 9. To facilitate their guidance on the spherical unit 7 the tappet wheels are fitted with the sliding members 11 which are rotatably mounted on the interior of the wheel by means of the pins 12 and can be displaced in 10 the grooves 10 of the unit 7. The tappet wheels 2 can be adjusted by the adjusting member 13 which can be rotated in the bearing 15 by the pin 14, the pins 14 and the adjusting members 13 being rotatable by means of a worm wheel segment 16 or any other suitable device, such as 15 levers or the like. The adjusting members 13 for both wheels 2 may be coupled together to insure positive motion of the members 13 and the wheels 2. According to the drawing, the worm wheel segments 16 for both wheels 2 are for this purpose adjustable by a common hand wheel 25, as indicated in Figs. 1 and 2, and corresponding common spindle and transmission members.
- I claim:—
1. Feed mechanism for debarking machines comprising a pair of wheels adapted to impart rotary motion and forward motion in a longitudinal direction to the timber being debarked, a supporting shaft for each wheel disposed parallel to the longitudinal axis of said timber, a spherical bearing member on each shaft provided with a peripheral groove, a sliding member in each of said grooves joined to a corresponding one of said wheels for orientably journaling each said wheel on a corresponding said spherical bearing member, a U-shaped adjusting member for each wheel through which the outer edge of said wheel moves, a pin carrying each said adjusting member, a fixed bearing carrying each said pin, said pin extending substantially perpendicularly to the axis of said wheel, and means to rotate said pin thereby to rotate said adjusting member about an axis perpendicular to the axis of said wheel.
2. Feed mechanism for debarking machines comprising a pair of wheels adapted to impart rotary motion and forward motion in a longitudinal direction to the timber being debarked, a supporting shaft for each wheel disposed parallel to the longitudinal axis of said timber, a spherical bearing member on each shaft provided with a peripheral groove, a sliding member in each of said grooves joined to a corresponding one of said wheels for orientably journaling each said wheel on a corresponding said spherical bearing member, and a U-shaped adjusting member for each wheel through which the rim of said wheel moves, said adjusting member being adapted and mounted to orient said wheel about an axis perpendicular to the axis of said wheel.
3. Feed mechanism for debarking machines comprising a pair of wheels adapted to impart rotary motion and forward motion in a longitudinal direction to the timber being debarked, a supporting shaft for each wheel disposed parallel to the longitudinal axis of said timber, each said wheel consisting of two interconnected parts and a one-piece dentated rim surrounding said parts, a spherical bearing member on each shaft provided with a peripheral groove, a sliding member in each of said grooves joined to a corresponding one of said wheels for orientably journaling each said wheel on a corresponding said spherical bearing member, and a U-shaped adjusting member for each wheel through which the lateral sides of said rim slide, said adjusting member being adapted and mounted to orient said wheel about an axis perpendicular to the axis of said wheel.
4. Feed mechanism for debarking machines comprising a pair of wheels adapted to impart rotary motion and forward motion in a longitudinal direction to the timber being debarked, a supporting shaft for each wheel disposed parallel to the longitudinal axis of said timber, a spherical bearing member on each shaft provided with a peripheral groove, a sliding member in each of said grooves joined to a corresponding one of said wheels for orientably journaling each said wheel on a corresponding said spherical bearing member, a U-shaped adjusting member for each wheel through which the outer edge of said wheel moves, a pin carrying each said adjusting member, a fixed bearing carrying each said pin, said pin extending substantially perpendicularly to the axis of said wheel, and means to rotate said pin thereby to rotate said adjusting member about an axis perpendicular to the axis of said wheel.
5. Feed mechanism for debarking machines comprising a pair of wheels adapted to impart rotary motion and forward motion in a longitudinal direction to the timber being debarked, a supporting shaft for each wheel disposed parallel to the longitudinal axis of said timber, a spherical bearing member on each shaft provided with a peripheral groove, a sliding member in each of said grooves joined to a corresponding one of said wheels for orientably journaling each said wheel on a corresponding said spherical bearing member, a U-shaped adjusting member for each wheel through which the outer edge of said wheel moves, a pin carrying each said adjusting member, a fixed bearing carrying each said pin, said pin extending substantially perpendicularly to the axis of said wheel, and means to rotate said pin thereby to rotate said adjusting member about an axis perpendicular to the axis of said wheel.
6. Feed mechanism for debarking machines comprising a pair of wheels adapted to impart rotary motion and forward motion in a longitudinal direction to the timber being debarked, a supporting shaft for each wheel disposed parallel to the longitudinal axis of said timber, a spherical bearing member on each shaft provided with a peripheral groove, a sliding member in each of said grooves joined to a corresponding one of said wheels for orientably journaling each said wheel on a corresponding said spherical bearing member, a U-shaped adjusting member for each wheel through which the outer edge of said wheel moves, a pin carrying each said adjusting member, a fixed bearing carrying each said pin, said pin extending substantially perpendicularly to the axis of said wheel, and means to rotate said pin thereby to rotate said adjusting member about an axis perpendicular to the axis of said wheel.

ALBERT BEZNER.
